UNITED STATES PATENT OFFICE.

ANDREW H. WALSTROM, OF BIRMINGHAM, ALABAMA.

COKE-OVEN COVER.

No. 809,344.

Specification of Letters Patent.

Patented Jan. 9, 1906.

Application filed December 12, 1904. Serial No. 236,573.

To all whom it may concern:

Be it known that I, ANDREW H. WALSTROM, residing at Birmingham, in the county of Jefferson and State of Alabama, have invented 5 certain new and useful Improvements in Coke-Oven Covers, of which the following is a specification.

My invention comprehends a cover of circular or polygonal shape in plan view and 10 dome-like in vertical section composed of a plurality of surfaces on different planes, all of which radiate to a common center and toward the center of the oven, over which the said cover may be placed. Such cover has 15 its radiating-faces so correlative arranged whereby all parts of the cover will be exposed to practically the same heat-rays when the cover is either wholly or partially located over the oven, and the heat from the oven is 20 so distributed by reason of the different facings of the cover exposed to the heat-rays of the cover that the contraction and expansion of the cover is so taken care of as to prevent buckling.

25 Subordinately, my invention consists in an oven-cover embodying the peculiar and novel arrangement of parts hereinafter fully described, pointed out in the claims, and illustrated in the accompanying drawings, in 30 which—

Figure 1 is a vertical section of a coke-oven with my improved cover applied for use. Fig. 2 is a similar view, the cover being but partially over the oven to open part thereof 35 to atmosphere. Fig. 3 is a plan view of the preferred form of my improved cover. Fig. 4 is a diagram illustrating the geometrical arrangement of the different radii of the surface of the form of cover shown in Figs. 1 and 40 3. Fig. 5 is a vertical section, and Fig. 6 is a plan view of a modified construction of my improved oven-cover. Figs. 7 and 8 are sectional and plan views, respectively, of a further modification of my invention hereinafter 45 referred to.

In the generic arrangement of my invention I provide a cover of a dome-like shape in cross-section having a plurality of surfaces of different radii or planes all of which radiate 50 toward a common center, and in the preferred construction, as shown in Figs. 1 and 2, the cover A is of a circular shape in plan view and of a dished or dome shape in cross-section, and it is of a size to snugly fit over 55 and close the throat of the coke-oven B, which may be of any of the ordinary types.

The cover A is formed with a plurality of surfaces that merge with one another to produce, as it were, a continuous surface over the entire internal face of the cover; but the 60 several surfaces (indicated by 1 2 3 4 5 in the drawings) are correlative so disposed that they all reflect toward the center of the oven in crossed rays, as indicated diagrammatically in Fig. 4. By reason of the peculiar construction of the cover—that is, forming the same of differently-curved subsurfaces, all of which radiate toward the center—I provide against an excessive heating of any one part of the cover and the consequent cracking 65 thereof, as well as providing for the uniform distribution of all the heat-rays from the oven that enter under the cover, even when but one portion thereof is held over the oven-throat and a portion of the said oven is open 70 to atmosphere. By reference to Fig. 4 it will be readily apparent that while the radii of the several different subsurfaces cross, those at one side of the central radial surfaces (designated 1) cross at that side only, 75 while those at the other side correspondingly cross on said other side only.

A cover such as before described and illustrated in Fig. 1 has five different surfaces, each on a different radius, and the several 85 different surfaces in the preferred construction are so disposed that their lines of juncture lie in parallel horizontal planes and that the radius of each successive surface increases 90 from the base toward the top of the cover.

Another and important advantage of my invention is that when drafting an oven during different stages of burning the operator in charge sets the cover but partially over the oven, as shown in Fig. 1, and leaves, say, one 95 fourth to one-half of the oven-throat open to the atmosphere. When in this position, by reason of the peculiar arrangement of the facing on the inside of the cover, all parts of the cover will be practically exposed to the 100 same heat-rays, although but one-half of the cover is directly over the top of the oven, since the different radial faces of the cover serve to cause a crossed radiation of the direct rays emanating from the oven and that 105 enter under the cover and toward the center of the cover, from whence they reflect back over that part of the cover that is not directly over the oven. The position last stated 110 of the cover is required during the operation of burning in the coal, and when this is accomplished the cover is then placed entirely

over the oven until it is ready to draw, at which time the coke in the oven will be at white heat.

In Figs. 7 and 8 is illustrated a slightly-modified form of my invention in which the cover has a polygonal shape in plan view, the central or crown portion a of which is curved on a twelve-inch radius, and the remainder is composed of four tiers of faces, and each tier comprises a plurality of faces (twenty being shown) on different angles, but merging with one another and retaining the same angles to each other.

In Figs. 5 and 6 I have illustrated a further modification of my invention which embodies substantially the construction shown in Figs. 7 and 8, the difference being that the cover is round in plan view and the several horizontal tiers of faces designated a' , a^2 , a^3 , and a^4 , beginning from the bottom up to the central curved top a , are disposed at different angles to each other, but extend entirely around and are not broken up into a number of independent surfaces, as in Figs. 7 and 8.

By providing a cover having a plurality of differentially-arranged surfaces, each struck on a different radius or inclined at a different angle with the cross-sectional shape of substantially spherical shape, I find that by sealing the edges of the cover with sand the said cover seldom gets hot, although the oven contents be at white heat.

Another and very important advantage obtained in the practical application of my invention is that the cover is much lighter in weight than that of the ordinary coke-oven cover, which usually weighs from one hundred and fifty to two hundred pounds, whereas in my construction the cover weighs between twenty-five and thirty pounds, thus making it easy to handle and economical in its manufacture.

Having thus described my invention, what I claim, and desire to secure by Letters Patent, is—

1. An oven - cover having a substantial dome shape, whose radiating-surface comprises a plurality of distinct circular subsurfaces.

2. An oven - cover having a substantial dome shape, whose radiating-surface comprises a plurality of distinct circular subsurfaces, integrally formed with each other.

3. A coke-oven cover of substantial dome shape composed of a plurality of curved surfaces of different radii having their centers of curvature regularly arranged around the axial line of the oven-cover substantially as shown and described.

4. A dome-shaped oven-cover formed of a single member having a plurality of longitudinally and transversely curved circular surfaces, each surface being curved on independent radii.

5. A dome-shaped oven-cover of an integral structure comprising a plurality of subsurfaces each formed as a circular band, each of different radii of curvature and each curved transversely on different radii, the radius of the transverse curvature of each successive surface increasing from the base of the cover toward the top thereof substantially as shown and described.

6. A dome-shaped oven-cover of an integral structure comprising a plurality of circular subsurfaces successively joining with each other, the line of juncture of each surface with the other lying in parallel horizontal planes substantially as shown and described.

7. An oven-cover of an integral structure and of substantial dome shape, comprising a plurality of surface bands each of which bands being transversely curved, the radius of transverse curvature of each successive band being different from the other, the lines of juncture between successive bands forming circles and lying in parallel horizontal planes, substantially as shown and described.

8. An oven - cover having a substantial dome shape whose radiating-surface comprises a plurality of distinct subsurfaces integrally formed with each other, the lines of juncture between the subsurfaces lying in parallel circles around a common axis.

ANDREW H. WALSTROM.
